UNITED STATES PATENT OFFICE.

JAMES L. SPINK AND ALBERT L. HOLLAND, OF MINNEAPOLIS, MINNESOTA;
SAID HOLLAND ASSIGNOR TO SAID SPINK.

IMPROVEMENT IN STEAM-BOILERS.

Specification forming part of Letters Patent No. **149,259**, dated March 31, 1874; application filed
January 29, 1874.

To all whom it may concern:

Be it known that we, JAMES L. SPINK and ALBERT L. HOLLAND, of Minneapolis, in the county of Hennepin and State of Minnesota, have invented a new and Improved Steam-Boiler; and we do hereby declare that the following is a full, clear, and exact description of the same, reference being had to the accompanying drawing forming a part of this specification, in which the figure is a front elevation of a boiler, showing our invention applied to it.

The invention relates to means whereby steam-boilers may be made more efficient and convenient.

The invention will first be fully described in connection with all that is necessary to a full understanding thereof, and then pointed out in the claim.

A represents a boiler with return-flues, and having the subjacent pipe B connecting with a pipe-coil, C. The latter has a pipe, D, which connects it with cylinder E that is conjoined with the boiler by intervening pipes F F that enter just below the water-level. G is a blow-

off pipe; H, the fire-box surrounded by fire-brick; I, the air-chamber that receives all the heat and transmits it. The blow-off pipes for the cylinder E all finally unite in one, and may be operated together.

This construction promotes a continuous circulation of the water, and produces in the water a uniformity of temperature, which is a great desideratum.

Having thus described our invention, what we claim as new, and desire to secure by Letters Patent, is—

The combination of the boiler A and steam-generating sections, composed of heating-tube E, connecting branch pipes F and intermediate heating-coil C, connected to the bottom of the boiler by pipe B, and to the heating-tube E by pipe D, by which means circulation in the boiler is maintained, substantially as described.

JAMES L. SPINK.
ALBERT L. HOLLAND.
